James L. Jackson
Design for a Picture Frame & Summericker No. 2
Statistical Survey, 1870s

Des 441

James L. Jackson, New York, N.Y.
Letters Patent No 441. Dated Feb 9, 1852.

The Schedule referred to in these Letters Patent, and making part of the same

To all whom it may concern:

Be it known that I, James L Jackson, of the City, County and State of New York, have invented or produced a certain new and original design for a grate frame, and Summer piece, and I do hereby declare the following to be a full, clear, and exact description of the same, reference being had to the accompanying drawing making a part thereof, and which represents one half as finished up, the other in outline, showing by section the projection of the parts herein enumerated.

The outer margin of the grate frame which is square, is finished with a light plain moulding a, and the inner margin having its sides parallel with the outer one, except at its corners, where it is rounded off is finished with a plain bead moulding b, leaving a plain low sunk panel c, between said bead, and the convex and concave mouldings d, e. On the base, which rises a few inches from the bottom of the jamb, is placed a stand g, out of which rises a stem h, with foliage i, and a running vine j, which entwines it. At about the centre in height of the stem h, is placed a full blown flower k, and the top of the stem is turned, and terminated in a foliated volute l, upon which is perched in the left hand corner of the frame a Bird of Paradise m, and in the right hand corner an eagle n, both of which birds have their wings partially spread.

With the exception of the birds, the ornaments on both sides are the same. In the centre of the panel, on the top part of the frame is a rich fruit piece o, surrounded and interspersed with foliage, the outer foliage terminating at bottom in volutes.

p, between which is a piece q, which extends down to the low panel c, and is decorated with foliated volutes r, on its sides and beads s, down its centre. From the bottom of the fruit piece o, and extending upwards, stands a cornucopia, reaching up to near the height of the fruit piece, and from the same point projects a foliated stem u, which sweeps around in a volute x, and terminates in a bunch of grapes v, pendant, and partially covered by highly wrought foliage w. The volutes, is coupled to the volute t, immediately over the heads of the birds, by an inverted decorated bracket y, and the space between the volutes finished by latticed work z.

The summer piece is made to fit the opening in the grate frame, so as to be removable at pleasure, the outer margin presenting a plain panel a'. On the bottom of the summer piece is placed a projecting bracket b', having on either side foliated volutes c', and said bracket supports in its centre a projection d', surmounted by an open work balustrade e', flanked by towers f', on either side, which towers are also supported on small brackets g', and decorated on their three sides by raised beads h'. On top of the towers f' are placed stands i', from which shoot a stem j', decorated with foliage and flowers in arabesque. The tops of the stems curve around in foliated volutes k', upon which are perched a Bird of Paradise l', with wings partially spread. In the centre of the summer piece on top, is a rich fruit piece m', resting upon vine leaves, and surrounded by a foliated border, which is coupled to the volutes k' by the scrolls n', and having the space between them decorated with latticed work o'.

The ground work p', (more distinctly seen in the separate fig, which is of an enlarged size) of the stems, foliage, birds &c. is wrought in diamond work. In the centre of a deeply sunken panel, inside of the above described ornaments, is a projecting

elliptical shield or crest q, in open work, radiating from the centre thereof which is supported at the bottom by a bracket r, resting against open lattices s, which together form a panel held in place by the double beads t, and connecting it with the summer piece. Outside of this ornament is chain bead work u, and a diamond ground work, upon which is placed an elliptical ornament v, with spear shaped foliage on top, and a cord and tassel on the bottom. The bottom of this recess rests upon a treulated ground w, in the middle of which is placed an ornamental arabesque figure x, the whole forming in general appearance a highly wrought bay window.

The sections A, B, C represent the projection of the several parts herein enumerated.

Having thus fully described the nature of my design, what I claim therein as new, and desire to secure by letters patent is the combination and arrangement of the ornamental figures herein represented, and forming an ornamental design for a grate frame, and summer piece.
